Attorney

UNITED STATES PATENT OFFICE.

PETER F. S. HACK, OF NEUDORF, SASKATCHEWAN, CANADA.

BROOM.

1,161,308.

Specification of Letters Patent. Patented Nov. 23, 1915.

Application filed March 24, 1914. Serial No. 826,960.

To all whom it may concern:

Be it known that I, PETER F. S. HACK, a subject of the King of Great Britain, and a resident of Neudorf, in the Province of Saskatchewan and Dominion of Canada, have invented certain new and useful Improvements in Brooms, of which the following is a specification, reference being had to the accompanying drawings.

This invention relates to certain new and useful improvements in brooms; and the object of my invention is to provide a broom having a head which can be readily detached and replaced by a new head.

With these and other objects in view, the present invention consists in the combination and arrangement of parts which will be hereinafter more fully described and finally pointed out in the appended claims it being further understood that changes in the specific structure shown and described may be made within the scope of the claims without departing from the spirit of the invention.

In the accompanying drawings forming a part of this specification and in which numerals of reference indicate similar parts in the several views: Figure 1, shows an elevational view with parts broken away of a broom embodying my invention, showing the casing door as open. Fig. 2, is a sectional view with parts broken away. Fig. 3, is an enlarged detached detail disclosing the slotted ear and the location of the spring plate. Fig. 4, shows a fragmentary detail disclosing the end of the carrying bar in contact with the spring. Fig. 5, shows a detail of the screw employed in securing the door to the casing housing.

In carrying out the aim of my invention I employ a casing 1, which includes the back 2' and the front 3'. The front 3' is very much shorter than the back, so that there is formed below this front 3' an access opening extending the full width of the casing, as clearly shown in Fig. 1. This casing ends in the handle socket 2, arranged to receive a suitable handle A, the lower end of which is slotted and adapted to be held upon a shoulder 3, formed of sheet metal and secured within the housing below the socket. A screw 13' holds the broom handle A against withdrawal. The access opening of the casing is closed by means of the door 4 having the pin sleeves 5, which give support to a suitable pin passing through the sleeve 6, forming part of the casing 1, as shown in

Fig. 1. The door 4 further has the screw sleeve 9, which is arranged to be held in alinement with the screw sleeves 7 and 8. A screw 10 passes through the sleeves 8 and 60 6 and screws into the sleeve 7 to securely hold the door in position to close the access opening, which extends entirely across one lower end of the casing. Upon one side I provide the apertured eye 12, which as 65 shown is accessible through the access opening, while located immediately opposite the apertured eye 12, is an ear 14 having the slot 15, this construction being shown in Fig. 3. The slotted ear is also accessible through 70 the access opening.

Secured within the casing and having its free end 16 behind the ear 14, is the spring plate 13, this construction being shown in Fig. 4. The upper portion of the spring 75 end 16 is flanged outward as shown at x, so that the carrying bar 11, which is arranged to be removably held within the eye 12 and slot 15, will be held in frictional contact with the end 16, the flanged portion permitting the carrying bar 11, to readily slide 80 against the end 16.

The broom head B, is made in any convenient manner to snugly fit into the casing, the broom straws being secured by means of 85 the usual strands a. This broom head B has an opening near the top arranged to removably receive the carrying bar 11, as shown in Fig. 2. Now after the broom head is worn it is simply necessary for the operator to remove the screw 10, open the door 4, and force the broom head B upward so that the bar 11, will be carried away from the spring end 16, and out of the slot 15, while the remaining end of the bar 11 will 95 readily slide out of the eye 12. The carrying bar 11, is then placed within a new broom head, and has one end first introduced into the eye 12 when the remaining end is carried into the slot 15 and against the spring end 16. The door 4, is then again closed and secured and the broom will be 100 ready for use.

From the foregoing it will be noticed that the broom casing and handle are not thrown away when the broom head is worn out, but form permanent and lasting implements arranged to receive the broom heads B.

It is of course understood that the broom head is of such a size that the same will 110 snugly fit into the casing.

The broom is simple and inexpensive in

construction and both durable and efficient in operation.

Having thus described my said invention, what I claim as new and desire to secure by 5 United States Letters Patent is:

1. A casing of the character described having an access opening upon one side and a handle socket, a door hingedly secured to said casing closing said access opening, means to secure said door, an apertured eye secured within said casing accessible through said opening, a slotted ear opposite said eye, a spring plate secured to said casing having one end behind said ear, a broom head, a carrying bar removably secured within said broom head having one end removably held within said eye and the other removably held within said ear, said spring contacting with said bar to removably hold the same, and a handle within said socket, as 15 20 and in the manner set forth.

2. A casing of the character described

having an access opening upon one side and a handle socket, a door hingedly secured to said casing closing said access opening, means to secure said door, an apertured eye secured within said casing accessible through 25 said opening, a slotted ear opposite said eye, a spring plate secured to said casing having one end behind said ear, a broom head, a carrying bar removably secured within said broom head having one end removably held within said eye and the other removably held within said ear, said spring contacting with said bar to removably hold the same, and a handle within said socket, as 30 35 and in the manner set forth.

In testimony whereof I affix my signature; in the presence of two witnesses.

PETER F. S. HACK.
